UNITED STATES PATENT OFFICE.

PETER B. PAGE, OF LORAIN, OHIO.

STRAIGHT-WAY VALVE.

SPECIFICATION forming part of Letters Patent No. 296,046, dated April 1, 1884.

Application filed July 24, 1883. (No model.)

To all whom it may concern:

Be it known that I, P. B. PAGE, a citizen of the United States, residing at Lorain, in the county of Lorain and State of Ohio, have 5 invented certain new and useful Improvements in Straight-Way Valves; and I do hereby declare the following to be a full, clear, and exact description of the invention, such as will enable others skilled in the art to which it app- 10 pertains to make and use the same.

The object of this invention is to produce a straight-way-valve system of simple, economical construction, and reliable automatic operation. These results are attained by the mechanism illustrated in the drawings herewith 15 filed as part hereof, in which the same letters of reference denote the same parts in the different views.

Figure 1 is a side elevation, partly in section. Fig. 2 is an end elevation, partly in section. Fig. 3 is a top view, partly in section. Fig. 4 is a front elevation of one of the valves. Fig. 5 is a top view of one of the parts detached.

25 A A A represent the shell forming the valve-chamber, and screw-threaded projections for connecting the same with the pipes or conduits.

A' is the top or cap, which is secured to 30 the shell A by screw-bolts a.

B is a screw-threaded spindle, the thread of which fits somewhat loosely in a correspondingly-screw-threaded perforation through the rectangular projection C, forming part of the 35 valve C'.

C' is a valve, the motion of which is dependent on the motion of the valve C'.

D is a link having central slot, d'', for clearing the spindle B, and connecting with 40 the valves C C' by its ends or rounded edges J J' entering corresponding recesses, d and d', in the sides thereof. The valve C' is provided with rectangular projections or arms G, made integrally therewith, and which enter and fit loosely in oblong recesses c in the valve C'.

E is a packing-nut, which screws into the stuffing-box E', and, by reason of the packing intervening between it and the collar on 50 the spindle, secures the same in position.

F is a lug or step in the bottom of the valve-chamber, with which the valve C' comes in contact preparatory to closing the conduits.

H H are inner projections or ribs of the shell A, in position corresponding with notches 55 I I' in the sides of the link D, which is thereby held in an inclined position, as shown, until the link reaches the curves at the ends of the ribs H, simultaneously with which the valve C'' engages with the lug F, by means of 60 which its further downward motion is prevented; and as the valve C' will still continue to move downward, and as the curved points at the lower ends of the ribs H will allow the link D to assume a position perpendicular to 65 the sides of the valves C' C'', the link will act as a cam and give the valves lateral motion, and force them tightly against the valve-seats a'. When the spindle B is turned in a direction to cause the valves to ascend, the valve 70 C' will start before the valve C'' begins to move, and will move sufficiently to bring the link D to the inclined position shown in Fig. 1, simultaneously with which the arms or projections G of the valve C' will engage with the 75 upper ends of the recesses c in the valve C'', and thereby cause it to ascend and open the corresponding conduits. The rectangular projection C of the valve C' will engage with the cap A' when the conduit-ways are opened, and 80 thus prevent the lower end of the valve C' from getting above the projection inside the shell, which forms the valve-seat a'.

The screw-threaded perforation in the projection of the valve C', through which the spindle B works, should be large enough to allow 85 the link D, when assuming a position at right angles to valves, to move the valve C' against the valve-seat a' without straining the spindle B.

Having explained the construction and operation of my improvement, what I claim as new, and desire to secure by Letters Patent, is—

The valves C C' C'' and the link D, all constructed as shown, in combination with the shell A, having inner ribs, H H, lug F, and spindle B, substantially as specified, and for the purpose set forth:

In testimony whereof I affix my signature in 90 presence of two witnesses.

PETER B. PAGE.
